CLAIM

The ornamental design for a cosmetic cabinet, as shown and described.

DESCRIPTION

FIG. 1 is a front, right and top perspective view of a cosmetic cabinet, showing my new design;

FIG. 2 is a front view thereof;

FIG. 3 is a rear view thereof;

FIG. 4 is a left side view thereof;

FIG. 5 is a right side view thereof;

FIG. 6 is a top plan view thereof;

FIG. 7 is a bottom plan view thereof; and,

FIG. 8 is an expanded perspective view of FIG. 1.

The broken lines shown in the drawings illustrate portions of the cosmetic cabinet that form no part of the claimed design.

1 Claim, 8 Drawing Sheets
